J. W. FORSYTH.

Churn.

No. 58,628.

Patented Oct. 9, 1866.

Inventor:

John W. Forsyth

by
D. E. Somes
atc' attorney.

UNITED STATES PATENT OFFICE.

JOHN W. FORSYTH, OF LEESBURG, VIRGINIA, ASSIGNOR TO HIMSELF, JOHN W. HEAD, AND NELSON HEAD.

IMPROVEMENT IN CHURNS.

Specification forming part of Letters Patent No. 58,628, dated October 9, 1866.

To all whom it may concern:

Be it known that I, JOHN W. FORSYTH, of Leesburg, Loudoun county, and State of Virginia, have invented a new and Improved Churn; and I do hereby declare that the following is a full and exact description thereof, reference being had to the accompanying drawings, and to the letters of reference marked thereon.

To enable others to make and use my invention, I will proceed to describe its construction and operation, as follows, viz:

F is a platform, of sufficient dimensions to suit the size of the machinery to be constructed thereon. On this platform F are two upright posts, E E', connected at their upper ends by a cross-piece, G. Between the posts described, situated vertically, is a large cog-wheel, A, through which passes a shaft, S, the journals of which work in the bearings H H', fixed in the upright posts. To the end K of this shaft is fixed a crank, or its equivalent, to which is applied the power.

Above the large wheel A, and gearing into it, is a small pinion, B. One end of the shaft on which this pinion is fixed extends beyond the post E' far enough to admit a fly-wheel, I, to be fixed on it. To the rim of this fly-wheel, at N, is attached a vertical shaft, C, by means of a pin. This shaft is also connected with

the dasher-shaft O of an ordinary churn-dasher at the joint J.

The vessel in which is held the cream for churning may be an ordinary or upright conical-shaped churn, (denoted by M,) to the dasher of which may be readily attached or detached the machinery already described.

The lid L of the vessel M is held in its place by means of hooks a a, attached to the sides of the vessel, and grasping into staples x x, fixed in the lid.

Attached to the bottom of the vessel M are strips D D D, of iron or other suitable material, which are slotted to admit staples h h h, in which are inverted hooks t t t, holding securely the vessel while the operation of churning is in progress.

What I claim as my invention, and desire to secure by Letters Patent, is—

The combination of the platform F with the posts E E', their connecting cross-piece G, wheel A, pinion B, fly-wheel I, pin N, shafts C and O, the vessel M, the hooks a a, securing the lid L, the slotted strips D D D, the hooks t t t, the staples h h h, as is described, and for the purpose set forth.

JOHN W. FORSYTH.
